UNITED STATES PATENT OFFICE.

WILLIAM ACKERMAN, OF TOWNSERS, NEW YORK, ASSIGNOR TO MERGENTHALER LINOTYPE COMPANY, A CORPORATION OF NEW YORK.

TYPOGRAPHICAL MACHINE.

Application filed September 5, 1925. Serial No. 54,670.

This invention relates to typographical machines, such as linotype machines of the general organization represented in Letters Patent of the United States to O. Mergenthaler, No. 436,582, wherein circulating matrices are released from a magazine in the order in which their characters are to appear in print and then assembled in line, the composed line transferred to the face of a slotted mold, the mold filled with molten metal to form a slug or linotype against the matrices which produce the type characters thereon, and the matrices thereafter returned through distributing mechanism to the magazine from which they started.

More particularly, it relates to that class of machines capable of handling matrix fonts differing as to the size and number of characters, such for instance as the seventy-two or fifty-five character display fonts and the ordinary ninety character text fonts now in use. In machines of this class, the keyboard mechanism includes means whereby the finger keys may be operatively connected to the magazine in use to effect the release of corresponding matrices of the contained font, whether the latter be a text font or a display font. This feature is important, since the matrices of the display fonts (being much thicker than those of the text fonts) are differently spaced in the magazine channels and are usually arranged in a different order as to character. A keyboard mechanism of the kind mentioned is fully set forth in the Kennedy Patents Nos. 1,397,967 and 1,397,974, to which reference may be had if desired.

The present invention contemplates an improved form of keyboard mechanism for accomplishing somewhat the same results. In the embodiment illustrated, the keyboard is provided with a single series of slides for the cam yokes, as usual, and these slides are operated from the finger keys through an intermediate series of connecting bails or levers, which may be adjusted at will to establish a set of direct connections between the various keys and the respective slides when an ordinary text font is in use, or a set of more or less indirect connections between certain selected keys and differently located slides of the series when a display font is in use. The particular form and

arrangement of the parts, as well as their mode of operation, will be best understood from the detailed description to follow.

In the accompanying drawings, the invention has been shown merely in preferred form and by way of example and obviously many changes and variations may be made therein without departing from its spirit. It is therefore to be understood that the invention is not limited to any specific form or embodiment, except in so far as such limitations are specified in the claims.

In the drawings:

Fig. 1 is a skeleton view of a linotype machine, equipped with the invention;

Fig. 2 is a side elevation, partly in section, of the improved keyboard and showing the bail box in its rearward position;

Fig. 3 is a side elevation of the rear part of the keyboard and showing the bail box in its forward position;

Figs. 4 and 5 are detailed perspective views illustrating one form of connecting bail employed and showing the bail in different operative positions;

Fig. 6 is a perspective view of another and more commonly employed form of connecting bail;

Fig. 7 is a detailed horizontal section taken through the bail box at one point in its length, showing an auxiliary guide plate for one of two adjacent bail arms;

Fig. 8 is a perspective view of still another form of connecting bail, one which is used when the same actuating slide is operated by the finger key in either adjusted position of the bail box;

Fig. 9 is a similar view, showing the means employed for locking the idle keys out of action;

Figs. 10 and 11 are perspective views of the form of connecting bail shown in Fig. 6 and showing it in different operative positions;

Figs. 12 and 13 are perspective views of another form of connecting bail, the form used in operating adjacent actuating slides—and showing it in different operative positions;

Fig. 14 is a diagrammatic view, showing the relation between the keyboard devices and the respective magazines; and

Fig. 15 is a plan view, partly diagram-

matic, of the keyboard mechanism, showing the connections between the first tier of finger keys and the corresponding group of connecting devices.

5 As shown in Fig. 1, the machine herein illustrated is equipped with two regular magazines A and a special magazine A¹, which are arranged to be raised and lowered in the well-known manner by the operation 10 of the hand crank S, so as to bring any selected magazine in operative relation to the assembling and distributing mechanisms. As these mechanisms form no part of the present invention, they need not be dealt 15 with further, although it will be understood that they should be capable of handling the different fonts employed.

The magazines A are each provided with ninety-one grooved channels spaced apart in the usual way to adapt them to contain the matrices of an ordinary ninety character or text font, whereas the magazine A¹ is provided with only seventy-three grooved channels spaced apart in a different manner to 25 adapt it to contain the matrices of a seventy-two character or display font, these two standard fonts being merely selected for purposes of illustration. Each magazine is provided with a series of matrix releasing 30 escapements a which, when the magazine is brought into operative position, are actuated through the medium of the pivoted levers E by the reeds E¹, the latter in turn being operated (Fig. 2) by the yoke E² arranged 35 in banks and provided with the cams or eccentrics E³, adapted under the influence of trip dogs E⁴ to cooperate with the underlying power-driven rolls E⁵. The trip dogs E⁴, as usual, are actuated by a series of 40 vertical slides H, guided in the fixed part of the keyboard frame, and operated in the manner about to be described from the keyboard F.

As before stated, the present invention 45 contemplates certain improvements whereby the keyboard F may be operatively connected to either the display magazine A¹ or the text magazine A so that like matrices of the two fonts (i. e. matrices bearing like characters) may be released from their respective magazines by the operation of the same finger keys, notwithstanding their different location in the magazine channels. This is accomplished by the employment of a series 50 of rocking levers or bails, designated M, N, O, P and Q; located at the rear of the keyboard and disposed in superposed groups, one for each tier of finger keys, the bails of the respective groups being pivotally mounted 55 upon transverse rods J¹ fitted into the end walls of a box or frame J. The box J is adjustable forwardly and rearwardly in order to set the various bails as a unit in one or the other of two different positions. In 60 their rearward position the bails serve to

connect all of the finger keys of the keyboard to the respective actuating slides H above referred to, so as to effect the release of the text matrices from a magazine A; whereas, in their forward position, the bails serve to connect certain selected keys to differently located slides of the series, so as to effect the release of the display matrices from the magazine A¹.

The bails M, best shown in Figs. 6, 10 and 11, are employed for the most part in making up the connections and are of the two-arm variety, the arms M¹ at one end being longer than the arms M² at the opposite end. The longer bail arms M¹ extend forwardly 75 between adjacent slides H so as to engage from below studs H¹ projecting laterally therefrom and to engage from above reduced end portions F³ of the finger keys F¹. It is in this way that the actuating slides are 80 connected to and operated by the finger keys, it being noted at this point that the reduced end portions F³ are sufficiently long to maintain their engagement with the forward ends of the bail arms M¹ in either adjusted position of the bails M. The shorter arms M² of the bails M are arranged to engage in notches H² formed in the rear edges of certain selected ones of the slides H when the bails occupy their forward position (see Fig. 11) but are adapted to become disengaged from said notches so as to stand clear of the slides, when the bails occupy their rearward position (see Fig. 10). It will be 85 observed that the longer bail arms M¹ are provided with recesses G spaced rearwardly from the studs H¹ a distance determined by the extent of the bail adjustment, such that when the bails occupy their forward position with the shorter arms M² in engagement with the notches H² of the selected slides (Fig. 11), the recesses G will lie beneath the studs H¹ and break the connection 90 previously existing between those slides and the associated finger keys. Under this condition 95 of adjustment, i. e. with the bails in their forward position, the motion of the finger keys will be imparted through the longer bail arms M¹, which move idly at such times, to the shorter bail arms M² and thence to the 100 selected slides H with which the latter arms are engaged. It will be understood that the bail arms M¹ and M² are differently spaced apart on the different bails, depending upon 105 the relative location of the two actuating slides with which each bail is associated. This is clearly depicted in the diagrams 110 of Figs. 14 and 15.

The bails N are of the single-arm variety 115 and are used in cases where two adjacent slides H are controlled from the same finger key. Such cases are indicated in the diagram of Fig. 14 for the characters t, a, ., H, R, F, Y, and the form and relation of 120 the parts are shown in detail in Figs. 12 and 125

13. It will be noted that these particular bails are provided with studs N^2 arranged to engage in the notches H^3 of the appropriate slides H and, like the longer arms M^1 of the 5 bails M , are recessed at G for the same reason. Accordingly, when the parts are in the position shown in Fig. 12, the finger key F^1 is operatively connected to one of the 10 slides H through the engagement of the bail arm with the stud H^1 , whereas, when the parts are in the position shown in Fig. 13, the key is operatively connected to the other slide H through the engagement of the stud N^2 in the notch H^3 of said slide. As a 15 matter of fact, the action of the bails N is identical with that of the bails M , the only difference being that the stud N^2 has been substituted for the short bail arm M^2 .

20 The bails O (shown in Figs. 4 and 5) are used in the rare cases where the longer and shorter arms of different bails operate on adjacent slides. These bails O are substantially the same as the bails M , except that the shorter arms O^2 engage studs H^4 on the 25 slides H , instead of engaging notches therein. The longer arms O^1 are identical with the bail arms M^1 and function in precisely the same way, being formed with recesses G for the same reasons.

30 It so happens that, in the present arrangement, certain of the slides H can be utilized in effecting the release of matrices with like characters of the text and display fonts. These particular characters (e, ;, D, 35 L, Z, etc.) are indicated by a marked circle at the bottom of the diagram shown in Fig. 14, and in such instances the single-armed bails or levers P shown in detail in Fig. 8 are employed. These bails are formed at 40 their forward ends so as to maintain engagement with both the associated slides H and finger keys F^1 in either adjusted position of the bails. In other words, the bails P afford a permanent connection between these 45 particular finger keys and the corresponding actuating slides, being useful primarily in permitting the adjustment of all the bails as a unit. Like connections, similarly indicated, are also employed for the last five 50 columns of matrices contained in the magazine A^1 . As shown, these matrices are disposed in vertical planes lying beyond the range of the escapement actuating reeds at the extreme right, and are released when the 55 corresponding keys are operated through the medium of a series of bails E^5 arranged above the keyboard F so as to be actuated by the appropriate reeds E^1 . These bails E^5 , although actuated when the ordinary 60 magazines are in use, move idly at such times since the group of escapement actuating levers E controlled thereby are located to the right of the escapements of that magazine. The arrangement in this respect is 65 like that shown and described in the Ken-

nedy Patent No. 1,397,974, to which reference may be had if desired.

Since only seventy-two of the ninety finger keys are used for the display fonts, means are herein provided for locking the 70 remaining eighteen keys out of action when the keyboard is connected to the magazine A^1 . The actuating slides H for such unused keys are controlled through the single-armed bails Q (Fig. 9) substantially the 75 same as the bails N without the studs N^2 and adjustable so as to make and break connection between the finger keys and the associated slides. These bails Q might, however, be identical with the bails P , since 80 locking means are provided to prevent their operation when in their forward position. The said locking means, in the present instance, (see Figs. 3 and 9) comprise stop 85 fingers L secured to the rear face of the keyboard back plate F^4 and arranged to engage from above the front ends of the bails Q when the latter are shifted forwardly to their inactive position (see dotted lines Fig. 9). Owing to the fact that the bails maintain a constant engagement with the reduced 90 end portions F^3 of the key levers, the latter will be locked or unlocked according to the adjusted position of the bails.

The operation of the parts will now be clear: When the box J is in its rearward position, the bails M , N , O , P , Q will connect all ninety finger keys F^1 directly with the respective actuating slides H , all the bails being engaged with the laterally projecting pins H^3 on the actuating slides. This is the condition of adjustment required for the release of matrices of a ninety character or text font from the magazine A . The other condition of adjustment is required 100 for the release of matrices of a seventy-two character or display font from the magazine A^1 . Under this other condition of adjustment, the box J is in its forward position and the bails serve to connect the 105 seventy-two active finger keys (those corresponding to the matrices of the display font) to the appropriate actuating slides H , the shorter arms M^2 and O^2 or the studs N^2 of the bails in this case being engaged with 110 the actuating slides and the longer bail arms being disengaged therefrom although maintaining their engagement with the finger keys. Of course, under both conditions of adjustment, the bails or levers P 115 will maintain the connection between the associated finger keys and the corresponding actuating slides, inasmuch as the same slides are used in both cases. The bails Q are only 120 active when in their rearward position, being locked against action by the fingers L in the forward position of the bails. It has already been pointed out that the form of the bails and the spacing of the bail arms 125 vary in accordance with the location of the 130

display matrices in the magazine channels, it being evident that when like matrices of the text and display fonts occupy differently located magazine channels, the finger keys will be alternately connected to those actuating slides which operate the escapements of such differently located channels. When a text font is in use, the connections between the finger keys and the magazine are the same as ordinarily, although, of course, made up in a different way. When a display font is in use, the connections will be altogether different, and these connections are shown by the diagram of Fig. 14. From this diagram, any one of the key connections may be easily traced. Take, for example, the letter v: The finger key F^1 bearing this letter is engaged by the longer arm of the bail M (indicated by the bold lines in every case), which is connected to the actuating slide H normally associated with the j finger key. Such slide, after having been disengaged from the j finger key by the forward adjustment of the bails, will respond to the operation of the v finger key and trip the overlying cam yoke E^2 , the latter operating the overlying reed E^1 for the escapement controlling the release of the display matrices bearing the character v in the magazine A^1 . The connections from the other keys may also be traced in like manner.

The manner of adjusting the connecting bails or levers will now be described, reference being directed to Figs. 1, 2, 3 and 15. As shown best in Figs. 3 and 15, the box J is supported by two pairs of parallel links R, R^1 , pivoted at their lower ends to a fixed bracket R^2 on the keyboard frame and pivotally connected at their upper ends to a cross member J^5 on each of the end walls of said box. The latter is thus rendered capable of being adjusted back and forth in a substantially horizontal path to establish the connections above described. In order to limit such adjustment of the box in either direction so as to locate the bails in their proper adjusted positions, the end walls of the box J are provided with lugs J^6 , which engage the keyboard post F^6 in the forward position of the box (Fig. 3) and which engage fingers F^7 on the posts in the retracted position of the box. Since each adjustment is comparatively small (about $1/4''$), and to obviate danger of breakage of the parts during adjustment, the box J is preferably adjusted through the medium of a spring. Thus, a spring J^7 (see Fig. 1) is arranged between the short arms of a pair of cooperating cam faced levers J^8, J^9 , having shoulders J^{10} and loosely mounted on an extended fulcrum pin R^3 of the link R . A hand lever K , pivoted at K^1 , is provided at its rear end with a roller K^2 arranged to engage the cam faced levers J^8, J^9 and rock them about the

fulcrum pin R^3 as the hand lever is operated, such motion being imparted to the pin and thence to the parallel links R, R^1 by a short crank arm J^{11} which is alternately engaged by the shoulders J^{10} of the cam faced levers J^8, J^9 . As a result of this arrangement, when the hand lever K is pushed upwardly the roller K^2 rides down over the cam face of the lever J^8 and releases the power stored up in the spring J^7 . As the roller passes onto the longer arm of the lever J^9 , the latter is depressed and the shoulder J^{10} of the lever J^8 is pulled by the spring up against a stud J^{12} on the arm J^{11} , so that further depression of the lever J^9 stretches the spring until the latter gains sufficient power to overcome the inertia of the box J , when it will be shifted forwardly against the keyboard post and held there under tension in the operative position shown in Fig. 3. When the hand lever is pushed downwardly, a similar action takes place but in the opposite direction.

The bails are guided in their rocking movements by separate elongated slots J^3 formed in the front wall J^2 of the box and in some cases by similar slots formed in the rear box wall J^4 . When the arms of two bails are so closely arranged as to prevent the use of separate guiding slots, one of the bails (as in Fig. 7) is provided with an auxiliary arm G^1 which is arranged in a slot J^3 formed at a convenient place in the box wall.

Having thus described my invention, what I claim and desire to secure by Letters Patent of the United States is as follows:

1. In a keyboard mechanism for typographical machines, the combination of a finger key, an actuating member, and a device directly engaged with both the finger key and actuating member for operatively connecting said parts, said device being adjustable to break such connection when required.

2. In a keyboard mechanism for typographical machines, the combination of a finger key, an actuating member, an adjustable connecting device arranged between said parts and adapted to be directly engaged therewith, and means for adjusting said device to make or break connection between the finger key and the actuating member as required.

3. In a keyboard mechanism for typographical machines, the combination of a finger key, an actuating member, a device operatively connecting said parts and adjustable to break such connection when desired, and a locking element arranged to engage the connecting device in its adjusted position, for locking the key out of action when said connection is broken.

4. In a keyboard mechanism for typographical machines, the combination of a finger key, two actuating members, and an

adjustable intermediate device for operatively connecting the key to either of said members to the exclusion of the other, said device being arranged in constant direct engagement with the finger key and adapted to be engaged directly with one or the other of the actuating members in its different adjusted positions.

5. In a keyboard mechanism for typographical machines, the combination of a finger key, two actuating members, a device for operatively connecting the key to either of said members to the exclusion of the other, an adjustable support wherein the connecting device is mounted, and means for adjusting the support to establish one or the other of said connections, as required.

6. In a keyboard mechanism for typographical machines, the combination of two actuating members, a fixed frame wherein the members are mounted, a finger key, and an intermediate adjustable device for operatively connecting the key to one or the other of the actuating members as required, said device being arranged in constant direct engagement with the finger key and adapted to be engaged directly with one or the other of the actuating members in its different adjusted positions.

30. 7. In a keyboard mechanism for typographical machines, the combination of two actuating members, a finger key, and an adjustable device serving in one position to connect the key to one of said members and in another position to connect the key to the other of said members.

8. In a keyboard mechanism for typographical machines, the combination of a series of finger keys, a corresponding series of actuating members, a fixed frame wherein the members are mounted, intermediate adjustable devices for establishing direct or indirect connections between the finger keys and the actuating members, and means for effecting the required adjustment of said devices.

40. 9. In a keyboard mechanism for typographical machines, the combination of a series of finger keys, a corresponding series of actuating members, adjustable devices serving in one position to connect the various finger keys to the respective members and in another position to connect certain selected keys to differently located members of the series, and means for adjusting said devices to either of said positions as required.

50. 10. In a keyboard mechanism for typographical machines, the combination of a series of finger keys, a corresponding series of actuating members, devices normally connecting the various keys to the respective members and adjustable to connect a lesser number of said keys to differently located members of the series, and means for lock-

ing the remaining keys out of action at the time of such adjustment.

11. In a keyboard mechanism for typographical machines, the combination of a series of finger keys, a corresponding series of actuating members, devices normally connecting the various keys to the respective members and adjustable to connect a lesser number of said keys to differently located members of the series, and means arranged when the connecting devices are thus adjusted to engage such of them as are associated with the remaining keys and lock the latter out of action.

12. In a keyboard mechanism for typographical machines, the combination of a series of finger keys, a corresponding series of actuating slides, a series of adjustable bails or levers serving in one position to connect the various keys to the respective slides and in another position to connect certain selected keys with differently located slides of the series, and means for adjusting the bails or levers to either of said positions, as required.

13. In a keyboard mechanism for typographical machines, the combination of a series of finger keys, a corresponding series of actuating slides, a series of bails or levers having constant engagement with the respective keys, an adjustable frame wherein the bails or levers are pivotally mounted, and means for adjusting the frame to different operative positions, the said bails or levers serving to connect the various keys to the respective slides when the frame is in one position and certain selected keys to differently located slides of the series when the frame is in another position.

14. In a keyboard mechanism for typographical machines, the combination of a series of actuating slides, a corresponding series of finger keys having their rear ends arranged adjacent the respective slides, and a series of bails or levers adjustable to establish direct connections between the various finger keys and the respective slides or indirect connections between certain selected keys and differently located slides of the series.

15. In a keyboard mechanism for typographical machines, the combination of a finger key, an actuating slide, and an intermediate connecting bail or lever adjustable to two different positions, the said bail or lever being arranged to maintain engagement with the finger key in both positions and to make and break connection with the actuating slide when adjusted to its different alternate positions.

16. In a keyboard mechanism for typographical machines, the combination of a finger key, two actuating slides, and an intermediate connecting bail or lever adjust-

able to two different positions, the said bail or lever being arranged to maintain engagement with the finger key in both positions and to make and break connection with the 5 two actuating slides alternately when adjusted back and forth between its two positions.

17. A keyboard mechanism as set forth in

claim 12, characterized by the fact that the actuating slides or members therein referred to control the operation of power-operated cam yokes or similar elements which actuate the matrix releasing escapements. 10

In testimony whereof, I have affixed my signature hereto.

WILLIAM ACKERMAN.
